UNITED STATES PATENT OFFICE.

ALBERT LATHAM, OF BEVERLY, MASSACHUSETTS, ASSIGNOR TO UNITED SHOE MACHINERY COMPANY, OF PATERSON, NEW JERSEY, A CORPORATION OF NEW JERSEY.

SHOE-SEWING MACHINE.

1,092,580.

Specification of Letters Patent.

Patented Apr. 7, 1914.

Application filed January 26, 1911. Serial No. 604,844.

To all whom it may concern:

Be it known that I, ALBERT LATHAM, a citizen of the United States, residing at Beverly, in the county of Essex and State of Massachusetts, have invented certain new and useful Improvements in Shoe-Sewing Machines; and I do hereby declare the following to be a full, clear, and exact description of the invention, such as will enable others skilled in the art to which it appertains to make and use the same.

The invention relates to inseam sewing machines such as are used in the manufacture of boots and shoes in uniting the uppers, insoles, and welts of welt shoes.

The primary object of the invention is to provide novel and improved means for severing the welt at the completion of the shoe, and for presenting the end of the welt in proper relation to the shoe at the beginning of the sewing of the seam whereby the welt may be severed close to the end of the inseam, and the seam may be started close to the end of the welt, with a resulting economy in the welting used. To these ends the welt severing devices are arranged to sever the welt back of the sewing point, and means is provided for feeding the welting to project its end the proper distance beyond the sewing point preparatory to operating upon another shoe. By arranging the severing devices the proper distance back of the sewing point, any desired length of unattached welt may be provided for at one end of the inseam, and by proper adjustment of the welt feeding devices the same or any desired length of unattached welt may be provided for at the other end of the inseam. Thus the welt may be severed at a uniform distance from the end of the inseam, and the inseam be started at a uniform distance from the end of the welting without any care or skill on the part of the operator, and the welt may be so severed and the welting so fed as to avoid all waste of welting.

Further objects of the invention are to provide improved means for severing and holding the thread whereby the end of the thread is held under tension during the first part of the loop drawing stroke of the needle in forming the first stitch and the proper drawing of the loop through the work is insured, a novel and improved construction of welt guide whereby the welt is firmly

held during the operation of the stitch forming devices and is released so that it may move freely through the guide during the feed of the shoe or during the feed of the welt, and a novel and improved means for holding the welt guide up to the shoe during at least one cycle of operations of the sewing mechanism at the beginning of the sewing operation.

To these ends the invention consists in the features of construction and combination of parts hereinafter described and referred to in the claims.

The features of the invention will be readily understood from an inspection of the accompanying drawings and the following detailed description of the mechanism illustrated therein.

In the drawings Figure 1 is a right-hand side elevation of a sewing machine embodying the features of the invention in their preferred forms; Fig. 2 is a left-hand side elevation of the machine; Fig. 3 is a sectional plan view showing the mechanism for guiding and manipulating the welt; Fig. 4 is a front elevation of the mechanism shown in Fig. 3; Fig. 5 is a side elevation partly in section showing the devices for retaining the welt guide in advanced position at the beginning of the sewing operation; Figs. 6, 7 and 8 are details illustrating the mode of operation of this mechanism; Fig. 8^a is a detailed perspective view of part of this mechanism; Fig. 9 is a sectional view on line 9—9, Fig. 3; Fig. 10 is a sectional view on line 10—10, Fig. 3; Fig. 11 is a detail sectional view on line 11—11 Fig. 10; Fig. 12 is a horizontal sectional view through the welt guide; Figs. 13, 14 and 15 are sectional views on lines 13—13, 14—14, and 15—15 respectively of Fig. 12; Fig. 16 is a detail front elevation showing the devices for severing and holding the end of the thread; Figs. 17 and 18 are sectional views on lines 17—17 and 18—18 respectively of Fig. 16; Fig. 19 is a side elevation looking toward the left in Fig. 16, showing the thread holding clamp in position for releasing the end of the thread; and Fig. 20 is a sectional view on line 20—20, Fig. 17.

In the drawings the invention is shown embodied in the inseam sewing machine shown and described in the application of William C. Meyer, Serial No. 568,248, filed

June 22, 1910, and except so far as modified and changed by the embodiment of the invention therein, the construction and mode of operation of the machine illustrated is the same as that of said application.

The machine illustrated is provided with a curved hook needle 1, a needle guide 2, a looper 3, a thread arm 4, a channel guide 5, an awl 6, a take-up 7, an auxiliary take-up 8, and tension devices 9, which are constructed and arranged as in the application above referred to, and are operated from the cam shaft 10 of the machine through mechanisms which are fully described in the above application, and which will be readily understood by anyone skilled in the art from an inspection of the drawings in the present application. The machine is also provided with a welt guide 11 formed on or secured to the forward end of an arm 12 which is pivotally connected to the forward end of the welt guide slide and to the pivoted arm 13 which supports the forward end of the welt guide slide. As shown, the arm 13 is bifurcated to embrace the welt guide arm 12 and the arms 12 and 13 are connected by pivot pins 14 and 15. The pivot pin 14 also forms the pivotal connection between the forward end of the welt guide slide and the arms 12 and 13 (Fig. 12). The rear end of the arm 12 is provided with a roll engaging a fixed cam 16 which imparts an oscillating movement to the welt guide as it is advanced and retracted. The welt guide slide is formed in two sections 17 and 18 which are connected together by a yielding connection 19 so that the rear section 18 may be retracted independently of the front section when the welt guide is held in advanced position at the beginning of the sewing operation by the mechanism hereinafter described. During the normal running of the machine the welt guide slide is advanced and retracted to move the welt guide toward and from the shoe by the spring 20 and the oscillating lever 21 which is connected with the rear section 18 of the slide through the clutches 22 and a clutch actuating block 23 such as fully described in the above application.

In the construction shown, the means for severing the welt at the completion of the sewing operation consists of a knife blade 24 arranged to reciprocate transversely through the welt guide at the proper distance back of the sewing point. The blade is secured in a knife block 25 mounted in a guideway formed in the welt arm 12. The mechanism for actuating the knife block comprises a rock shaft 26 connected with the knife block through an arm 27, and also provided with an arm 28 through which it is rocked to advance and retract the knife block (Figs. 1, 3, 4, and 9 to 13). The arm 28 carries a roll 29 arranged to be engaged by the front end of a slide 30 and to enter

a vertical slot 31 formed at the front end of the slide. The slide is connected to one arm 32 of a bell crank lever, the other arm 33 of which is connected with a spring 34 which normally holds the slide 30 in retracted position. The arm 33 of the bell crank lever is connected through a rod 35 with a treadle (not shown) through which the operator may actuate the bell crank lever to advance the welt cutting knife. As soon as the treadle is released the spring 34 acts to retract the slide 30 and thus return the knife to its normal retracted position.

The welt severing knife is arranged to sever the welt in advance of the sewing point, and after the welt is severed it is necessary to feed forward the welting so that its end will project the proper distance beyond the sewing point at the beginning of the next sewing operation. The machine is accordingly provided with means for advancing the welt through the welt guide, and this means is preferably connected with the knife actuating mechanism in such manner that it will be operated by the return of the knife actuating mechanism to normal position. In the construction shown the welt feeding means comprises a feed roll 36 against the periphery of which the welting is held by a pressure roll 37 (Figs. 1, 3, 4, 10 and 11). The periphery of the feed roll 36 is preferably knurled or roughened to secure a firm grip upon the welting, and the pressure roll 37 is mounted in a lever 38 and is held yieldingly against the welting by a spring 39. The feed roll 36 is loosely mounted on the shaft 40 so that it may turn freely and not interfere with the forward movement of the welt during the sewing operation. The roll is operated to feed forward the welt after the welt has been severed at the completion of the sewing operation by a clutch sleeve 41 keyed on the shaft 40 and provided with fine ratchet teeth adapted to engage similar teeth formed on the end of the roll 36. The clutch sleeve is held in engagement with the end of the feed roll by a light spring 42, and the teeth are so shaped that they offer no substantial resistance to the forward movement of the roll as the welt is drawn forward. The inner end of the shaft 40 is connected through beveled gears 43 with a shaft 44, to the lower end of which a spiral gear 45 is secured. The gear 45 is engaged by a gear segment 46 formed on one arm of a lever 47, the other arm of which is pivotally connected to the front end of an actuating rod 48. The rear end of the rod 48 is supported in an arm 49 secured to the rear end of the knife actuating slide 30, and adjustable nuts 50 are arranged on the rod on opposite sides of the arm. The forward and return movements of the rod 48 are determined by stop collars 51 and 52 adjustably secured on the

70

130

rod and arranged to engage opposite sides of a fixed stop lug 53. The nuts 50 are so adjusted that there is sufficient lost motion between the knife actuating slide 30 and the feed actuating rod 48 to secure the withdrawal of the welt cutting knife from the welt guide before the welt is fed forward. The forward movement imparted to the slide 30 and rod 48 is determined by the stop 52, or by a stop screw 54 on the slide 30. The extent to which the welt is fed forward by the welt feeding roll may be varied by adjusting the stop collar 51, since the position of this collar determines the retracting movement imparted to the feed actuating rod 48.

When the treadle is depressed to actuate the welt severing knife the rod 48 is advanced and rocks the shaft 40. The connections are such that at this time the clutch 42 is moved in a direction to ride idly over the teeth in the end of the feed roll 36. When the treadle is released and the slide 30 retracted the knife is drawn back out of the welt guide so that it will not interfere with the forward feed of the welt. During this movement of the knife the arm 49 moves idly along the rod 48, and after the knife has been withdrawn out of the path of the welt the arm engages the rear nut 50 and retracts the rod 48. The rearward movement of the rod 48 rotates the shaft 40 and clutch 41 in a direction to turn the feed roll 36 forward and feed forward the welt. The stop collar 51 is so adjusted that it will engage the stop block 53 and arrest the rotation of the feed roll when the end of the welt has been projected beyond the sewing point to the desired extent.

The welt guide should act to hold the welt accurately in position during the operation of the stitch forming devices and at the same time should be so constructed as to offer the minimum resistance to the forward feed of the welt during the sewing operation and to the passage of the welt through the welt guide when the welt is advanced after it is severed from the completed shoe. The welt guide of the present machine is accordingly so constructed that it may be contracted to hold the welt and may be expanded to release the welt and allow it to move freely through the guide. In the construction shown the welt guide is contracted and expanded by advancing and retracting that part of the guide which engages the outer edge of the welt and acts as a gage for guiding the edge of the welt. The preferred construction of gage is shown in Figs. 12, 14 and 15. As here shown, the welt is guided as it enters the welt guide, by an anti-traction roll 55 carried by a block 56 which is adjustably secured to the welt guide arm 12 by a screw 57 passing through a slot 58 in the arm. This roll is so adjusted that the

welt will freely enter the welt guide, and will not be held or clamped between the roll and the front edge of the guide. In advance of the guide 15, two rolls 59 are arranged which engage the outer edge of the welt and press it firmly against the forward edge of the welt guide. These rolls form the gage for acting on the outer edge of the welt, and are carried in a slide 60 which is mounted to reciprocate in a guideway formed in the welt arm 12. The slide is advanced to contract the welt guide and thus hold the welt during the operation of the stitch forming devices, and is retracted to expand the welt guide and thus release the welt during the feed of the shoe by means of a cam groove 61 formed in a cam disk 62, and arranged to engage a roll on the end of a lever 63 which is connected with the slide. The connections between the lever and slide in the construction shown consist of a segment 64 formed on the lower end of the lever and arranged to engage a rack formed on a sleeve 65 which surrounds a rod 66. The forward end of the rod 66 is screwed into the rear end of a slide 67 the front end of which carries an arm 68 connected with the slide 60 by a pivot block 69. The block 69 is mounted in a vertical slot formed on the under side of the slide 60, and turns freely on a bearing 70 formed on the arm 68. The sleeve 65 is mounted to slide in a bearing 71 and is held from turning by a screw 72 engaging a key-way formed in the sleeve. The sleeve is connected with the rod 68 through springs 73 and 74 arranged in recesses in the ends of the sleeve and interposed between the bottoms of the recesses and collars 75 and 76 secured on the rod. The collar 76 is screw-threaded on the rod so that it may be adjusted to vary the tension of the springs. The rear end of the rod is provided with a knurled collar 77 through which the rod may be turned to adjust the position of the gage rolls 59 in accordance with the width of welt being used. The spring 73 forms yielding connection between the lever 63 and the gage slide, so that the gage is forced yieldingly against the welt when the slide is advanced, and the spring 74 forms a yielding connection between the lever and gage slide which may yield to allow the lever to move independently of the gage when the welt guide is retained in advanced position at the beginning of the sewing operation, as hereinafter described. When the machine is turned into position for the removal of the work at the completion of a shoe, the cam 61 is brought into position to retract the gage slide so that the welt is released and is free to move through the welt guide when the welt cutting and feeding devices are operated.

In order that the thread may be conveniently severed after a shoe has been sewed,

and the end of the thread held in proper position until the beginning of the sewing operation upon another shoe, the machine is provided with thread severing and thread holding devices. In the construction shown the thread severing device consists of two cutter blades 78 and 79 which for convenience are secured upon the arm 80 at the end of the rock shaft through which the needle guard is operated. When the machine is turned into position for the removal of a completed shoe, the upper end of the arm 80 is in its forward position, and the thread severing knives are in proper position for severing the thread. In removing the shoe after the welt has been severed the operator raises it and then moves it downward. The upward movement of the shoe carries the thread up along the inclined under edge of the blade 78, and as soon as the thread passes above the blade it springs inward into the V between the blades 78 and 79, and is severed when the shoe is moved downward. The upward movement of the shoe to bring the thread to the thread severing devices carries that part of the thread which extends from the looper 3 to the seam up between the jaws of a thread holding device which is arranged between the end of the looper and the thread severing device. In the construction shown, the thread holding device consists of two jaws 81 and 82. The jaw 81 is formed on the outer end of a pivot stud 83 which is mounted in a bearing in the plate 84 which forms a part of the frame of the machine. The jaw 82 is provided with a hollow stud 85 which engages a recess formed in the outer end of the stud 83, and the plate 82 is forced yielding toward the plate 81 by a spring 86 (Figs. 16 to 20). The jaws are held from relative swinging movement by a pin 87 projecting from the jaw 81 through a hole in the jaw 82. The jaws are opened and closed by means of a disk 88 surrounding the stud 85, and provided with cam lugs 89 co-operating with cam recesses 90 in the jaw 82. The disk 88 is also provided with a lug 91 adapted to play between two stops 92 formed on a stop plate 93 which is secured to the frame plate 84. The thread holder is held in normal position by a rack pin 95 which engages teeth formed in the stud 83, and is operated by a leaf spring 96 arranged to engage the head of the pin. The spring operates to hold the thread holder in the position indicated in Fig. 16, at which time the lug 91 is in engagement with the right-hand stop 92, and the cam lugs 89 are in register with the recesses 90, so that the jaws of the holder are held closed. When the shoe is lifted to sever the thread the thread passes up between the jaws 81 and 82 and is firmly gripped by the jaws. When the machine is started at the beginning of the sewing operation upon the next shoe, the looper lays the thread in the eye of the needle, and then the needle is retracted to draw a loop of thread through the work. During this movement of the needle the thread holder continues to hold the end of the thread so that the thread leading from the eye of the needle is held under tension until the loop has been drawn into the work. During this movement of the needle the thread holder swings toward the right in Fig. 16 against the tension of the spring 96, and after the loop has been drawn into the work the lug 91 strikes the left stop 92, arresting the movement of the cam disk 88. During the continued forward movement of the thread holding jaws the cam lugs 89 ride out of the recesses 90, forcing the jaw 82 away from the jaw 81 and releasing the thread. The thread holder immediately snaps back to normal position under the influence of the spring 96, the lug 91 strikes against the right-hand stop 92, shifting the disk 88 so that the thread holding jaws are closed, ready to again grip and hold the thread at the end of the sewing operation. The tension put upon the thread by the thread holding jaws may be regulated by an adjusting screw 97 which determines the tension of the spring 96. At the beginning of the sewing operation the welt guide is held in advanced position for at least one cycle of operations performed by the machine, so that the end of the welt is held close to the shoe until it has been securely attached thereto by the stitch forming devices. These devices are so constructed that they are moved into position to hold the welt guide when the rotation of the cam shaft of the machine is reversed to throw off the tension and move the parts into position for removal of the shoe at the completion of the sewing operation. These devices are best shown in Figs. 2 to 8. As here shown, the lever 98 which is rocked to throw off the tension when the cam shaft of the machine is reversed at the completion of the sewing operation, is connected by a rod 99 with an arm 100 which is mounted on a stud 101. The arm 100 is provided with a hub, the end of which is connected by a coupling with the hub 102 of a second arm 103 which is also mounted on the stud 101. The outer end of the second arm is pivotally connected to a vertical rod 104, the lower end of which passes through an arm 105 secured to the rock shaft carrying the arm 13 which supports the welt guide slide. The rod is provided with a collar 106 which engages the arm 105 when the lever 98 is rocked by the reversal of the cam shaft, and swings the arm 13 to retract the welt guide. When the machine is again started, the welt guide moves forward and is held in its advanced position.

during the formation of the first stitch by devices rendered operative when the cam shaft was reversed. In the construction shown these devices comprise a latch pin 5 107 mounted in a recess formed in the end of the pivot stud 15 which is secured in the upper end of the arm 13. The head of the pin is normally held in position above the stud 15 by a spring 108. The latch pin is 10 arranged to coöperate with the front end of an arm 109 which projects forward through a sleeve 110 mounted to turn freely on the hubs of the arms 100 and 103. A second arm 111 projects from the sleeve 110 15 and carries a spring operated retaining pin 112, the outer end of which is V-shaped and is arranged to engage one or the other of two notches 113 formed in a retaining plate 114. The sleeve 110 is also provided 20 with a third arm 115 which carries devices through which the sleeve is rocked to disengage the arm 109 from the latch pin 107, and to render the welt guide retaining devices inactive.

25 During the sewing operation the retaining pin 112 is in engagement with the lower notch 113, and the arm 109 is retained in its upper position where it is out of the path of the pin 107. With the parts in this 30 position the welt guide is free to be advanced and retracted during each cycle of operations of the stitch forming devices in the usual manner. When the cam shaft of the machine is reversed at the end of the 35 sewing operation preparatory to removing the shoe, the arm 103 is swung downward, and by its engagement with a lug 116 on the arm 109, moves the arm 109 down into active position. This movement of the arm 40 109 brings the retaining pin 112 into the upper notch 113, so that the arm 109 is retained in this position. When the arm 109 is thus moved downward the welt guide has been retracted through the downward 45 movement of the rod 104 so that the lever 109 strikes the upper end of the pin 107 and depresses the pin into the position shown in Fig. 2. This movement of the arm 109 also swings the rear end of the 50 arm 115 up toward the cam shaft of the machine, and brings the devices on the rear end of the arm into position to be acted upon by a lug 117 on the cam disk 62. The devices on the rear end of the arm 115 55 comprise a tripping lug 118 formed on a disk 119 which is secured to a pivot shaft 120 carried by the rear end of the arm. The lug 118 is broader than the body of the disk 119, and its base forms short segmental 60 flanges projecting from the opposite sides of the disk. The body of the disk fits within the bifurcated end of the arm 115, and the inner surfaces of the base of the lug 118 project over the curved end of the arm, 65 as indicated in Figs. 3, 5 and 8. The disk

119 is also provided with a tooth 121 adapted to coöperate with the lug 117. The disk is also provided with a stop shoulder or tooth 122 adapted to be engaged by a latching pawl 123 pivoted on the arm 115. The outer 70 end of the pivot shaft 120 is provided with an arm 124 which is connected with the pawl 123 by a spring 125. The spring acts to hold the pawl yieldingly against the disk 119, and also tends to swing the disk in a direction to hold the shoulder 122 against the end of the pawl. When the arm 115 is moved upward the pawl 123 is disengaged from the shoulder 122, so that the shoulder is carried beyond the end of the pawl, as 80 indicated in Fig. 5. The pawl 123 is thus disengaged from the shoulder 122 by a pawl 126 mounted on an arm 127 secured to the frame of the machine.

The pawl 126 is provided at its upper end 85 with a hook adapted to engage a hook 128 on the pawl 123. When the arms 109 and 115 are in normal position the pawl 126 is engaged with the pawl 123, as indicated in Fig. 8. When the arm 115 moves upward 90 the pawl 123 is engaged by the pawl 126 and is swung toward the left in Fig. 8, and toward the right in Figs. 2 and 5, thus disengaging the pawl 123 from the shoulder on the disk 119, and allowing the disk to swing 95 into the position indicated in Figs. 2 and 5. After the pawl 123 has been thus operated, the swinging of the pawl 123 during the continued upward movement of the arm 115 disengages the pawls 126 and 123. When 100 the disk 119 is released by the pawl 123 it is swung by the spring 125 into position to bring the tooth 121 into the path of the lug 117. The disk, however, is free to swing in the end of the arm 115, so that the lug 105 117 may pass idly by the end of the lever as the cam shaft is reversed or turned backward. When the machine is started, and the cam shaft is turned forward or in the direction of the arrow in Fig. 5, the lug 117 110 during the first revolution of the cam shaft acts upon the tooth 121 and turns the disk 119 into position to bring the lug 118 into the path of the lug 117. This movement of the disk also brings the latching shoulder 115 122 into position to be engaged by the pawl 123 so that the lug 118 is retained in the path of the lug 117 on the cam shaft. Now during the second revolution of the cam shaft the lug 117 acts against the lug 118, 120 as indicated in Fig. 7. This tends to turn the disk 119 toward the left in Fig. 7, and movement of the disk in this direction is prevented by engagement of the tooth 121 with the upper end of the pawl 123, so that 125 the arm 115 is depressed into the position indicated in Fig. 8. This disengages the arm 109 from the pin 107, thus releasing the welt guide and moving the arm 109 into inactive position so that the welt guide may be 130

advanced and retracted in the usual manner during the continuance of the sewing operation. The downward movement of the arm 115 reengages the pawl 123 with the pawl 126, so that the pawl 126 may act to re-set the tripping devices on the end of the arm 115 when the arm is again raised at the completion of the sewing operation.

While it is preferred to employ the specific construction and arrangement of parts shown and described in embodying the invention in the machine of the application above referred to, it will be understood that this construction and arrangement is not essential, and may be varied and modified to best suit the conditions under which it is to be used, or the construction of the machine in which it is to be embodied.

Having explained the nature and object of the invention, and specifically described one form of machine in which it may be embodied, what I claim is:—

1. A shoe sewing machine, having, in combination, stitch forming devices including a curved hook needle and looper, a welt guide, means inactive during the sewing for severing the welt in advance of the sewing point, and means for actuating the welt severing means and for advancing the end of the welt beyond the sewing point after the completion of the sewing.

2. A shoe sewing machine, having, in combination, stitch forming devices including a curved hook needle and looper, a welt guide, a welt severing knife in advance of the sewing point, and mechanism under the control of the operator for actuating the knife and advancing the end of the welt beyond the sewing point after the completion of the sewing.

3. A shoe sewing machine, having, in combination, stitch forming devices including a curved hook needle and looper, a welt guide, a welt severing knife arranged to reciprocate transversely through the welt guide, welt advancing means inactive during the sewing, and mechanism for advancing and retracting the knife and actuating the welt advancing means after the completion of the sewing.

4. A shoe sewing machine, having, in combination, stitch forming devices including a curved hook needle and looper, a welt guide, a welt severing knife, welt feeding devices engaging the welt in advance of the knife, and mechanism for actuating the knife and welt feeding devices adjustable to vary the feed of the welt.

5. A shoe sewing machine, having, in combination, stitch forming devices, a welt guide, welt severing devices, means inactive during the sewing for advancing the welt through the guide after it is severed, and means for expanding the guide during the

advance of the welt, substantially as described.

6. A shoe sewing machine, having, in combination, stitch forming devices, welt severing devices, welt advancing means inactive during the sewing, and means for holding the welt during the operation of the stitch forming devices and for releasing the welt during the operation of the welt advancing means, substantially as described.

7. A shoe sewing machine, having, in combination, stitch forming devices, a welt guide having a gage for the outer edge of the welt, and means for reciprocating the gage to hold and release the welt, substantially as described.

8. A shoe sewing machine, having, in combination, stitch forming devices, a welt guide provided with a gage for the outer edge of the welt, and means for advancing the gage to hold the welt during the operation of the stitch forming devices and for retracting the gage during relative movement between the shoe and welt guide, substantially as described.

9. A shoe sewing machine, having, in combination, stitch forming devices, a welt guide, mechanism acting normally to retract the welt guide during each cycle of operations of the machine, a normally inactive device for preventing the retraction of the welt guide, mechanism actuated by a reversal of the cam shaft of the machine for moving the preventing device into position to engage and hold the welt guide when it is advanced upon starting the machine, and mechanism for rendering the preventing device inactive after the completion of at least one cycle of the operations of the machine, substantially as described.

10. A shoe sewing machine, having, in combination, stitch forming devices, a welt guide, mechanism acting normally to retract the welt guide during each cycle of operations of the machine, a retaining arm 109 for preventing the retraction of the welt guide, means for moving said arm into active position upon a reversal of the cam shaft of the machine, an arm 115 connected with the arm 109, a lug 117 on the cam shaft, a tripping lug 118 pivotally mounted on the arm 115 and provided with a tooth 121 and latching shoulder 122, a latching pawl 123, and means for disengaging the pawl from the shoulder 122 when the arm 109 is moved into active position, substantially as described.

11. A shoe sewing machine, having, in combination, stitch forming devices, a welt guide, mechanism acting normally to retract the welt guide during each cycle of operations of the machine, devices for preventing the retraction of the welt guide comprising a yielding latching pin connected

- with the welt guide and a coöperating locking arm, mechanism acting upon the reversal of the cam shaft to retract the welt guide and to depress the locking arm against the 5 end of the latch pin, and means operating when the machine is started to return the arm to inoperative position after at least one cycle of operations of the machine has been completed, substantially as described.
- 10 12. A shoe sewing machine, having, in combination, stitch forming devices, a welt guide, mechanism acting normally to retract the welt guide during each cycle of operations of the machine, a normally inactive 15 retaining device for preventing the retraction of the welt, and means acting upon the reversal of the machine for rendering said retaining device active, means for rendering said device again inactive comprising an arm connected with the retaining device, a lug 20 on the cam shaft, a disk 119 pivotally mounted on the end of the arm and provided with a lug 118, a tooth 121 and a shoulder 122, a spring 125 tending to hold the disk with the tooth 121 in the path of 25 the lug 117, a latching pawl 123 on the arm, and a re-setting pawl 126, substantially as described.

ALBERT LATHAM.
